UNITED STATES PATENT OFFICE

114,303

DESIGN FOR A KNEE REST FOR GARDENERS

John H. L. Sullivan, Roxbury, and Elmer B.
Thibedeau, Gloucester, Mass.

Application December 19, 1938, Serial No. 81,870

Term of patent 3½ years

To all whom it may concern:

Be it known that we, John H. L. Sullivan and Elmer B. Thibedeau, citizens of the United States, residing respectively at Roxbury, in the county of Suffolk, and at Gloucester, in the county of Essex, both in the Commonwealth of Massachusetts, have invented a new, original, and ornamental Design for a Knee Rest for Gardeners, of which the following is a specification, reference being had to the accompanying drawing, forming a part thereof.

The figure is a perspective view of the knee rest for gardeners, showing our design. The outer surface of the right upright element is substantially similar to that of the left end element.

We claim:

The ornamental design for a knee rest for gardeners, substantially as shown and described.

JOHN H. L. SULLIVAN.
ELMER B. THIBEDEAU.
